UNITED STATES PATENT OFFICE.

WALTER S. DONALDSON, OF OMAHA, NEBRASKA.

REAMER ATTACHMENT FOR DIE-STOCKS.

1,141,045.

Specification of Letters Patent. Patented May 25, 1915.

Application filed August 4, 1914. Serial No. 854,990.

To all whom it may concern:

Be it known that I, WALTER S. DONALDSON, a citizen of the United States, residing at Omaha, in the county of Douglas and 5 State of Nebraska, have invented certain new and useful Improvements in Reamer Attachments for Die-Stocks; and I do hereby declare the following to be a full, clear, and exact description of the invention, such 10 as will enable others skilled in the art to which it appertains to make and use the same.

This invention relates to reamer attachments for pipe-cutting die-stocks, and has 15 for its object to provide a device of this character of improved and simplified construction, which may be quickly and conveniently attached to several of the standard forms of die-stocks.

With this and other objects in view, the 20 invention consists in the novel construction, arrangement and the formation of parts as will be hereinafter specifically described, claimed and illustrated in the accompanying 25 drawings, in which,

Figure 1 represents a side elevation of the attachment applied to a die-stock of a standard type, Fig. 2 represents a sectional view therethrough, partly broken away, Fig. 3 30 represents a side elevation of the reamer removed, Fig. 4 represents a transverse sectional view on the line 4—4 of Fig. 3, Fig. 5 represents a top plan view of the reamer, partly broken away, Fig. 6 represents a 35 transverse sectional view on the line 6—6 of Fig. 1, and, Fig. 7 represents an enlarged detail view, partly broken away, of the reamer and holder therefor.

Referring to the drawings in detail, 40 wherein similar reference numerals designate corresponding parts throughout the several views, the numeral 10 indicates the body of a die-stock of standard construction provided with the usual handles 11, the dies 45 12 and the throat 13.

A plate 14 is secured to the top face of the body 10 by suitable bolts 15 and is provided with a right angularly extending hollow barrel 16 having an inwardly directed 50 flange 17 at its upper end and an open lower end. The bore 18 of the barrel 16 is rectilinear and the inwardly directed flange 17 is provided with screwthreads to

receive the sleeve 19 having a circular bore 55 receiving the shank 20 of the holder 21. A threaded cap 22 is fitted on the upper end of the sleeve 19 and a nut 23 is fitted on the upper extremity of the shank 20 for adjustably securing the latter. An expansion spring 24 is coiled about the shank 20 60 and engaged at its opposite extremities against the cap 22 and the enlargement constituting a part of the holder 21 which latter is of rectilinear formation and rotatably and slidably mounted in the rectilinear bore 65 18 of the barrel 16.

The reamer 25, preferably of the rose type is positioned within the concaved end of the holder 21 and is provided with a shank 26 positioned within a recess 27 in the holder 70 and secured against removal by a tapered pin.

In operation, the sleeve 19 is adjusted relative to the barrel 16 to engage the reamer 25 within the end of the pipe 28, and the 75 reamer, as it will be understood, is resiliently retained in operative position against the end of the pipe by the tension of the spring 24 which may be adjusted by the nut 23.

What I claim is:

1. In combination, a barrel having a rectilinear bore and an inwardly directed flange at one end providing a circular opening having screw threads, a sleeve adjustably positioned within said threaded opening, a holder positioned within said sleeve, a reamer in said holder, and means for resiliently retaining said holder in extended position.

2. In combination, a barrel having a rectilinear bore and a threaded aperture in one end, a sleeve adjustably positioned in said aperture, a holder of rectilinear formation slidably and non-rotatably mounted in said 85 bore, a shank on said holder extending exteriorly of the upper end of said sleeve, means for normally retaining said holder in downwardly extended position, means carried by the upper end of said shank for 95 limiting the downward movement thereof, and a reamer secured in said holder.

3. In combination, a barrel having a rectilinear bore and a threaded aperture in one end, a holder of rectilinear formation 105 non-rotatably and slidably mounted in said

rectilinear bore, a sleeve fitted in said threaded aperture, an apertured cap secured at the upper end of said sleeve, a shank on said holder projecting through said cap, a 5 nut on the upper extremity of said shank, and a spring disposed between said shank and said holder.

In testimony whereof I affix my signature in presence of two witnesses.

WALTER S. DONALDSON.
